UNITED STATES PATENT OFFICE.

HORACE WYMAN, OF WORCESTER, MASSACHUSETTS, ASSIGNOR TO THE
CROMPTON LOOM WORKS, OF SAME PLACE.

LOOM.

SPECIFICATION forming part of Letters Patent No. 412,689, dated October 8, 1889.

Application filed March 9, 1889. Serial No. 302,685. (No model.)

To all whom it may concern:

Be it known that I, HORACE WYMAN, of Worcester, county of Worcester, State of Massachusetts, have invented an Improvement in 5 Looms, of which the following description, in connection with the accompanying drawings, is a specification, like letters on the drawings representing like parts.

In looms as now commonly made wherein 10 eveners are employed to act upon two jacks and place the harness-frame at a common level before forming the shed, the cording connecting the jacks with the harness-frame is subjected to very considerable strain, which, 15 besides unduly stretching the leather portions of the said cording, also results in straining the working parts of the loom unnecessarily.

To obviate unnecessary straining of the cording as the frames are evened and just before 20 making the shed, I have added to the shedding mechanism of the loom a compensating device, herein shown as a cam, which, while the bars of the evener are in engagement with both sets of jacks, and only at that 25 time, (the jacks at such time being moved away from the lifter preparatory to the action of the pattern-surface upon the jacks to select them for the formation of a new shed,) temporarily lessens or relieves the tension on the 30 harness-frame cording, so that while the pattern-surface acts to select the jacks the harness-cording will be subject to less strain than it would otherwise have.

To accomplish this part of my invention I 35 have mounted one set of the sheaves, over which runs the cording going to the harness-frames, so that the said set of sheaves may move or yield at the time stated to relieve the strain on the cording, and, as herein shown, 40 the time at which the said sheaves may move together to lessen the strain is determined by the compensating device, the latter at all other times, and especially when the shed is being made, acting to keep the set of sheaves 45 rigidly in place.

I do not desire to limit my invention for 50 obviating undue strain on the cording to permitting the particular set of sheaves shown to yield just before the formation of each shed, 55 for my invention may be practiced with any usual set of sheaves.

Another part of my invention has to do with throwing the picking mechanism out of action automatically upon the breaking or failure of the weft-thread, as will be described.

55

Figure 1 is a partial left-hand side elevation of a loom embodying my improvements. Fig. 2 is a partial front elevation of the right-hand end of the loom shown in Fig. 1. Fig. 3 is a sectional detail showing some of the 60 parts employed at the left-hand end of the loom to actuate the shaft instrumental in moving the lifter and the evener-bars, most of the said parts being omitted from Fig. 1. Fig. 4 is a partial front elevation of the loom, 65 chiefly, however, to show the manner of connecting the harness-frames and jacks, the said figure also showing the compensating device referred to, part of the means for moving the lifter, and the evener-bars, and the pattern-surface; Fig. 4^a, a sectional detail to show the shape of the jacks, the evener and lifter being in section. Fig. 5 is a sectional detail, looking down upon the picking shaft or cam in the lower part of the loom, the said figure 75 showing the devices employed for shifting the positions of the picking balls or rolls. Figs. 6, 7, 8, and 9, and 9^a and 9^b, are details to be referred to, forming part of the said picking mechanism. Fig. 10 is a detail in plan view 80 showing part of the breast-beam and means whereby the failure of the weft may be made to automatically operate the lever controlling the picking mechanism; Fig. 10^a, a detail of the latch 145 and projection 24. Fig. 11 is a 85 detail showing part of the lay with the dagger to act upon the slide-bar shown in Figs. 1 and 10, and the sliding bar p. Fig. 12 is a detail showing one of the links 112, intermediate the lower levers and the connecting 90 wires. Fig. 13 is a detail showing one of the links 115. Fig. 14 shows the rocking sheave or carrying-frame.

The loom-frame A is and may be of usual shape to sustain the working parts. The 95 frame has suitable bearings for the picker-shaft A', upon one end of which is a gear A², which in practice may have at its outer face beveled teeth to be engaged by a beveled pinion A³, fast on a driving or main shaft A³, 100 having at one end any usual driving-pulley A⁴. The tooth-gear A² engages a toothed gear

A⁵, fast on the usual crank-shaft A⁶, the respective sizes of the said gears A² and A⁵ being such as to cause the picking and crank shafts to rotate in unison, each making turn 5 for turn alike. The usual cranks of the crank-shaft receive usual connecting-rods A⁷, which are joined in usual manner to the lay A⁸, said lay in practice carrying any usual drop-boxes. Each picker-stick B has its fulcrum on a like 10 to suitable stand B', herein shown as extended from the studs forming the journals for the lay-swords. The picker-sticks are connected by usual straps and links B² with arms B³ of a picker-shaft B⁴, having attached to it a wing 15 B⁵ of usual shape, which in practice will be struck at each rotation of the shafts A' A⁶ by a suitable roll or ball B⁶. The lower end of each picker-stick has attached to it any usual strap, as B⁷, and a spring, as B⁸, the spring 20 being connected to some rigid part, as to the floor, or it may be to a projection on the framework, the spring normally acting to keep the picker-stick in its outward position. The upper part of the frame has suitable bearings 25 for a rock-shaft k, having at its opposite ends arms i and l, each being suitably slotted for the reception of like adjustable crank pins or studs. The studs carried by the arms l at opposite sides of the loom have connected to 30 them suitable connecting-rods, as d³, which are fitted to the ends of the evener-bar, composed, essentially, of two parallel bars m³ l², located at a little distance apart, but connected and always moving together. The 35 studs of the said arms i at opposite sides of the loom have joined to them like connecting-rods c³, which in turn are joined to the ends of the lifter i², which, by the said connecting-rods, is reciprocated in suitable slots of the bracket 40 A²⁰, extended from the loom side. This bracket contains two sets of guides, as e² and d², in vertical slots of which are guided the jacks a² and b². Each jack a² has a hook at its inner 45 end, to which is attached the cording going to the upper side of the usual harness-frame h', a part of the said cording being composed of leather and being extended over a set of usual sheaves mounted upon a rod at the top of the loom-frame. Each like jack b² has connected 50 to its hooked end the cording, which, as will be hereinafter described, is made to depress a harness-frame.

My invention is not limited to the specific form of jack described, and I desire to include 55 as within the scope of my invention any usual jacks.

In this invention the cording h, extended from the jack b², and adapted to be connected with the under sides of a harness-frame h', is 60 extended over one of a series of sheaves 100, mounted upon a rod 101, carried in a movable or rocking frame 102, the said frame being shown as mounted loosely upon a rod 103, extended across the top of the loom. The said 65 frame has, as shown, an arm 104, provided at its outer end with a roller or other stud 105, which bears upon the compensating device

shown as a cam 106, herein represented as secured by a bolt 107 to one of the rocking arms, as i, at the end of the rock-shaft k; but in 70 practice each arm l and i may have a like cam to operate against an arm like 104, having a roll 105, but at the opposite ends of the frame 102, and cause the said sheaves 100 to move in a direction to lessen the strain on the 75 cording, the frame herein shown moving about the center 103. This cam is shown separately in Fig. 14. The connections h, extended from the jacks b² downwardly, have upper portions composed of leather, and their 80 lower portions 108 composed of wire having hooks at its opposite end. The lower end of each rod 108, instead of being connected directly to the outer end of one of a series of levers 109, pivoted at 110, is connected to a 85 thin metallic link 112, slotted at its upper ends, as at 113, (see Fig. 12,) to be engaged by the wire 108. The lower end of each link 112 may have an offset, so that the body of the link may lie in substantially the same 90 vertical plane as the lever 109, and, as herein shown, the link has a hollow hub 112^x, which enters a hole in the outer end of the lever 109, where it is held by a rivet 109^x, which in practice will have its end upset in a countersink at one side of the said link, such construction enabling the levers to be placed much closer together than would be possible if the wire-like rods were connected directly to the ends of the said levers, as heretofore 100 done; and, further, by the employment of the links a much stronger connection is made, and much wear upon the wire-like rods is obviated. The inner ends of the levers 109 are connected by narrow thin links 115, having 105 eyes at their upper and lower ends, the said eyes in turn being connected in suitable manner to the wires 116, extended up to the lower sides of the harness-frames.

The pattern-surface employed in connection with the shedding mechanism is and may be of usual construction—as, for instance, as common to United States Patent No. 264,864.

Herein the pattern-surface is shown as a chain 118, extended over a cylinder 119, having at or near one end a gear D¹⁶, which is engaged by a beveled gear D¹⁵ (see Fig. 1) at the upper end of a vertical shaft D¹⁴, having suitable bearings. This shaft has splined to it a hub D¹⁰, having clutch-teeth at its opposite ends and an annular central groove which is embraced by a forked arm D¹², attached to a slide-rod D¹³, having its bearings at 125 225. The slide-rod D¹³, at a point between its bearings, has attached to it a collar having a stud 226, (see Fig. 1,) which stud is embraced by one end of a hand-lever a², (see Fig. 4,) pivoted at a³. The shaft D¹⁴ has loose upon it at opposite sides of the said hub two beveled gears D⁸ and D⁹, each having the inner end of its hub toothed to be engaged by one or the other end of said hub D¹⁰, according to the direction in which it is desired to rotate the shaft D¹⁴. By moving the hand-lever a² the 130

hub D^{10} may be placed in central position between the gears D^8 or D^9 , or be engaged with one or the other of the said gears D^8 or D^9 , they being rotated continuously by a beveled gear D' , fast upon one end of a star-wheel D^4 , which is engaged and moved intermittently by a suitable pin-wheel D , rotated or carried by a cranked portion of the crank-shaft A^6 (see Fig. 3) outside the frame-work.

10 The devices described for actuating the pattern-surface are substantially the same as in United States Patent No. 264,864. The crank referred to as being carried by the crank-shaft A^6 outside the frame-work has connected to it a link 130, one end of which is attached to a stud of a rocking lever 131, (see Figs. 1 and 3,) an arm of the said lever having joined to it a connecting-rod 132, which is extended upwardly and attached to an arm 133, extended from the rock-shaft k referred to. (See Fig. 3.) Just before the protuberances of the pattern-surfaces are to act to lift the jacks preparatory to forming a shed the evener-bars m^2 l^2 are moved outwardly and 15 made to engage the outermost projections of the jacks and move them all outwardly, so as to close or "even," as it is called, the shed. In their outward movement the evener-bars m^2 l^2 remove the shoulders e^8 of the jacks from 20 contact with the lifter-bar i^2 just before the protuberances of the pattern-surface act to distribute the jacks for a new shed, and it is at this time that the compensating device referred to arrives in the position shown in Fig. 35 4, where it will be seen that the roller-stud enters the depression 135 (see Fig. 14) of the said compensating device, thus permitting the frame carrying the set of sheaves 100 to rock or move and permit the sheaves to move 40 bodily toward the jacks, thus temporarily relieving the harness-connections h , extending to the levers 109, from what would otherwise be excessive strain, or strain in excess of that to which they are subjected while the roller-stud travels upon the portions of the compensating device of greater radius, as when 45 the shed is being made.

Referring to the picking mechanism, the shaft A' has fastened to it near each side of the frame a hub, as r , the said hubs being rights and lefts, according to which side of the loom they are to be placed on. Each hub has a pivot, as r' , for the reception of the roll-carrier r^2 , it having a hole, as r^8 , to fit the said pivot r' . The roll-carrier has its outer end slotted, as shown at r^4 , Fig. 7, to receive the stud r^5 , upon which is mounted loosely the picking-roll B^6 . The roll-carrier has a lug, as r^7 , which, when the loom is in regular operation and the roll is in position to strike the shoe B^5 to effect the picking of the shuttle, engages a lug r^8 , near the end of the hub r , the engagement of the two lugs, as described, preventing twisting strain on the pivot r' . 55 Each roll-carrier r^2 has a finger or projection, as 3, (see Fig. 9^b), which enters a notch 60 of a collar s , loosely mounted upon the

shaft A' , so that the longitudinal movement of the said collar upon the said shaft will turn the carrier r^2 upon its pivot r' , as represented by dotted lines in Fig. 6, the carrier when in the full-line position actuating the picking-stick, the picking being suspended when the carrier is in the dotted-line position. To move these collars automatically to start 75 or stop the picking, I have provided the loom-frame at its opposite sides with like brackets, as s' , having suitable adjustable studs s^2 , one of the said studs having mounted upon it a lever s^3 and the other a lever s^4 , the inner 80 ends of each of the said levers having a roll or other stud, or being forked, as best shown in Fig. 7, where the lever s^4 is shown as partially broken off. The two levers s^3 s^4 are joined together by a connecting-rod s^5 , and the outer end s of the lever s^4 is made to enter the forked end of an upright lever 138, pivoted at 139 on the loom side. The breast-beam D (see Figs. 1 and 10) has at its inner side a bracket f , having at one edge a projection 24, the horizontal shelf of the said bracket receiving upon it a slide-bar p , provided with a projection 26, cam-shaped at its rear side, as best shown in Fig. 11. The hand-lever 138, pivoted at 139 and connected to the lever s^4 , has arranged just behind it a pin or projection 141 of an arm 142 of a rock-shaft 143, extended across the loom and provided with an arm 144, to which is jointed one end of a latch, as 145, the said latch normally engaging the said projection 24. The latch, as shown, has a pin or projection 146, which is extended across the slide p , so that when the latter is engaged by the usual dagger p^3 , common to United States Patent No. 365,012, and carried by the lay, (see Fig. 11,) the said slide-bar as it is moved toward the breast-beam causes the incline or cam 26 thereon to act on the pin 146 and remove the latch from the projection 24 referred to, thus letting the 95 spring 147 act to turn the rock-shaft 143 in the direction to cause the pin 148 to act on the lever 138 and turn it in a direction to stop the picking action, the lever 138 not, however, being so moved until after the weft fails. 115

Prior to my invention I am not aware that a latch has been locked in position when the loom was operated regularly, the said latch being under the control of a spring which, as soon as the latch is released through a dagger controlled by the feeler, causes the said spring to move the latch and connected parts to effect the automatic throwing out of action of the picking mechanism. 120

I have shown the rear end of the arm 142 as connected by a rod w with the lever a^2 , so that as the arm 142 is moved to actuate the lever 138 it also moves the lever a^2 automatically for a distance sufficient to place the hub D^{10} in central position with relation to the two gears D^8 D^9 , thus stopping the forward rotation of and leaving the pattern-surface at rest. 125

I am aware that in a loom having jacks

connected by cording from each end to the upper and lower sides of the harness-frames a sheave has been made to act upon and tighten the cording just as the eveners act upon the jacks to even the shed prior to distributing the jacks for a new shed, such tightening of the cording being necessary to insure the catching of a lifter and depressor upon the hooks of the jacks.

5 10 I claim—

10 15 1. A harness-frame, two jacks, cording to connect one end of one of the said jacks to the upper side of the harness-frame, a sheave to support the said cording, cording intermediate one end of the other of the said jacks and the under side of the harness-frame, and a sheave, as 100, over which the said cording is extended, combined with a movable sheave-carrying frame and with a compensating de-

20 25 vice to hold the frame against and strain the cording during the time that the shed is being formed and to move the said frame to reduce the strain on the cording when both of the said jacks are engaged by the evener, substantially as described.

25 30 2. A harness-frame, two jacks, cording to connect one end of one of the said jacks to the upper side of the harness-frame, a sheave to support the said cording, cording intermediate one end of the other of the said jacks and the under side of the harness-frame, and a sheave, as 100, over which the said cording is extended, combined with a movable sheave-carrying frame and with a compensating de-

35 40 vice having a cam-surface to act upon a roller or other stud 105 of the said sheave-carrying frame to hold the frame against and strain the cording during the time that the shed is being formed and to move the said frame to reduce the strain on the cording when both of the said jacks are engaged by the evener, substantially as described.

3. The cross-shaft A', provided with the hubs having lugs and the roller-carrying arms pivoted thereon, and the sleeve-hubs engaging the said roller-carrying arms loosely, combined with arms to engage the said sleeves, connections between the said arms, and a lever 138, to move the said arms to throw the rolls out of position and stop the picking, substantially as described.

4. A lever 138, to control the stopping and starting of the picking mechanism, and a latch, a projection to be engaged by and arrest the latch, a spring to normally draw the latch past the projection, and means to release the latch from the said projection, combined with means, substantially as described, between the said latch and lever, whereby when the latch is released from the projection the spring is made to move the lever 138 and stop the picking, substantially as described.

5. The lever a², the clutching-hub, connections between the said lever and hub to move the latter, a latch, a projection to be engaged by and arrest the latch, a spring to normally draw the latch past the projection, and means to release the latch from the said projection, combined with means, substantially as described, between the said latch and lever, whereby when the latch is released from the projection the spring is made to move the lever a² and place the said hub in position to stop the forward rotation of the pattern mechanism, substantially as described.

75 In testimony whereof I have signed my name to this specification in the presence of two subscribing witnesses.

HORACE WYMAN.
